(57) **CLAIM**

We claim the ornamental design for a bowl for vacuum waste system, as shown and described.

DESCRIPTION

FIG. 1 is a front perspective view of a bowl for vacuum waste system;

FIG. 2 is a front view of the design of FIG. 1;

FIG. 3 is a rear view of the design of FIG. 1;

FIG. 4 is a detailed perspective view of the back of the design of FIG. 1;

FIG. 5 is a side view of the design of FIG. 1;

FIG. 6 is another side view of the design of FIG. 1;

FIG. 7 is a top view of the design of FIG. 1;

FIG. 8 is a bottom view of the design of FIG. 1;

FIG. 9 is a detailed side perspective view of the design of FIG. 1;

FIG. 10 is a detailed bottom perspective view of the design of FIG. 1; and,

FIG. 11 is a further detailed bottom perspective view of the design of FIG. 1.
